UNITED STATES PATENT OFFICE.

RAYMOND W. DULL, OF CHICAGO, ILLINOIS, AND FRANK J. OAKES, OF INDIANAPOLIS, INDIANA, ASSIGNORS TO LINK-BELT COMPANY, OF CHICAGO, ILLINOIS, A CORPORATION OF ILLINOIS.

NOISELESS CHAIN.

Application filed January 30, 1924. Serial No. 689,421.

To all whom it may concern:

Be it known that we, RAYMOND W. DULL and FRANK J. OAKES, being citizens of the United States and residents, respectively, of Chicago, in the county of Cook and State of Illinois, and of Indianapolis, in the county of Marion and State of Indiana, have invented a certain new and useful Improvement in Noiseless Chains, of which the following is a specification.

Our invention relates to an improvement in chains, and has particular relation to a chain wherein each link is made up of a plurality of laterally aligned link elements joined by transverse pins.

One object of our invention is to provide a chain of this type which shall be particularly cheap to manufacture and easy to assemble. Another object is to lengthen the wear of such chain by increasing the bearing area of the relatively moving parts. Another object is to dispense with the necessity of using bushings to join the laterally aligned link parts. Other objects will appear from time to time in the course of the specification and claims.

We illustrate our invention more or less diagrammatically in the accompanying drawings, wherein—

Figure 1 is a plan view of a section of the chain with parts cut away;

Figure 2 is a side elevation with parts broken away;

Figures 3 and 4 are detailed longitudinal vertical sections on an enlarged scale.

Like parts are illustrated by like symbols throughout the specification and drawings.

The chain is made up of a plurality of links which consist, for example, of a flange link element A at each side of said link, said flange element being of relatively thick stock and being shaped with a relatively horizontal bottom A¹. The flange link elements A are mounted upon and connected together by pins B which are necked as at B¹, the outer end of the pin being upset as at B² to secure the flange link thereupon, and to prevent relative rotation of pin and flange link.

Intermediate the flange link sections A, A¹ are a plurality of thinner link sections C, which are herein illustrated as of substantially thinner stock than the flange links

A. They are also cut away as at C¹ so that each of said sections forms in effect two pointed teeth C² joined by an arched bridge C³ at the top of the link.

In a narrow chain the upsetting of the heads B² of the pins B is in general sufficient to prevent rotation of said pins in relation to the flange link sections A. In broader chains, however, we preferably cut away or shape the pin B positively to prevent its rotation in relation to the links. We may, for example, cut it away at a single point, as shown at B¹⁰ in Figure 3, or we may cut it away to make a plurality of planes, as at B¹² in Figure 3, it being necessary, however, that at least half, and preferably more than one-half, of the periphery of the pin should be arcuate and concentric, and that no part of the pin shall project beyond such arc. When the pin is so formed the link sections A and C are perforated to conform to the pin, and are thus positively held against rotation.

The pin is made relatively large in cross-section to increase its bearing area, and this bearing area is further increased by having those links or link sections which rotate in relation to the pin of thicker stock than those which do not. The links formed as above described are therefore joined together by relatively thick links or link sections which are spaced along the pin B by the thinner immovable link sections C. Thus we illustrate pairs of thick link sections D which are formed substantially like the link sections C, save for their increased thickness, and, like the link sections C, have an intermediate bridge D¹ and pointed teeth D² at each end. While we illustrate pairs of thick link sections D, under some circumstances we might prefer to use a single thick link section in the place of each pair. These thick link sections, which rotate about the pins B as the chain is bent in the course of its travel, present to the pins a maximum bearing surface. This bearing surface is increased both by the increase of the thickness of the rotating link sections D in relation to the non-rotating sections C, and by the use of a pin B of large cross section.

It will be realized that while we have illustrated an operative form of chain, nevertheless many changes may be made in the

size, shape, proportion and relation of parts without departing from the spirit of our invention.

The use and operation of our invention 5 are as follows:

When chain of the form herein illustrated is used, the thick side flange sections prevent the chain from slipping laterally from the sprockets or other members about which 10 it passes, the sprocket teeth penetrating between the pointed teeth of the inner link sections.

The chain is particularly simple to manufacture since it comprises only four separate 15 parts, namely the necked bearing pin, the thick stock side flange element, the thin stock elements C and the thick stock elements D. Of these the elements C and D may be made of like shape and differing 20 only in the thickness of the stock.

No bushing or any other special bearing members need be used, but the wear of the link sections on the pins is minimized by the increase of the bearing area, since the 25 link sections C which do not rotate in relation to the pins are made as thin as is consistent with their strength, and the thick link elements D which do rotate about the pin are of thicker stock and are more numerous than the thin elements C. This increase of the bearing surface of the moving parts is further emphasized by the use of the large diameter pins and the result is a simple, easy and cheaply manufactured 30 chain of maximum life.

We claim:

1. A chain having links each comprising a pair of relatively thick outer link sections, 40 cross pins at each end of said sections and connecting them, and inner link sections spaced along said pins and of thinner stock than said outer sections, said pins being of non-circular cross section, the apertures through the link sections being correspondingly shaped, said pins being arcuate in cross section throughout more than one half of their periphery, and being entirely enclosed within the circle of which said arcs 45 form parts, all said link sections being in direct contact with the cross pins and connecting members for the links, comprising link sections directly contacting and rotatable about the pins of the links.

2. In a chain, chain links comprising a 55 pair of relatively thick outer link sections, cross pins at each end of said sections and connecting them, and non-rotatable in relation thereto, inner link sections spaced along said pins and of thinner stock than said outer sections, and connections between such chain links comprising relatively thick link sections spaced along said cross pins between said thin inner link sections, and rotatable about said pins.

60 3. In a chain, chain links comprising a

pair of relatively thick outer link sections, cross pins at each end of said sections and connecting them, and non-rotatable in relation thereto, inner link sections spaced along said pins and of thinner stock than said outer sections, and connections between such chain links comprising relatively thick link sections spaced along said cross pins between said thin inner link sections, a plurality of such thick sections being interposed between each pair of thin link sections. 75

4. In a chain, chain links comprising a pair of relatively thick outer link sections, cross pins at each end of said sections and connecting them, and non-rotatable in relation thereto, inner link sections spaced along said pins and of thinner stock than said outer sections, means for preventing relative rotation of said pins and said link sections, and connections between such chain links 80 and rotatable about such pins, comprising relatively thick link sections spaced along said cross pins between said thin inner link sections. 85

5. In a chain, chain links comprising a 90 pair of relatively thick outer link sections, cross pins at each end of said sections and connecting them, and non-rotatable in relation thereto, inner link sections spaced along said pins and of thinner stock than said outer sections, said pins being of non-circular cross section, the apertures through the link sections being correspondingly shaped, and connections between such chain links comprising relatively thick link sections 95 spaced along said cross pins between said thin inner link sections, and rotatable about such pins. 100

6. In a chain, chain links comprising a plurality of link sections, cross pins passing through each end of said sections and connecting them, to form the link, and non-rotatable in relation thereto, and means for connecting said links comprising link sections mounted upon and rotatable about said pins, the pin engaging area of said rotatable link sections being substantially greater than the pin engaging area of the non-rotating sections. 110

7. In a chain, chain links each comprising a plurality of laterally spaced flat link elements of substantially the same thickness from end to end, cross pins passing through each end of said elements and connecting them to form the link, and non-rotatable in relation thereto, and means for connecting said links comprising flat link sections mounted upon and rotatable about and in direct engagement with said pins, said rotatable elements being substantially thicker 115 than said non-rotatable element and being of substantially the same thickness from end to end. 120

8. In a chain, chain links each comprising a plurality of laterally spaced link elements, 125

cross pins passing through each end of said elements and connecting them to form the link, the elements directly contacting the cross pins, and non-rotatable in relation thereto, and means for connecting said links comprising link sections mounted upon and rotatable about and in direct engagement with said pins, said rotatable elements being substantially thicker than said non-rotatable elements at their points of engagement with said pins.

9. A chain having links each comprising a plurality of laterally spaced link sections, cross pins at each end of said sections and

connecting them, said pins being of non-circular cross section, all said link sections being in direct contact with said pins, the apertures therethrough conforming to the cross section of the pins, and connecting members for the links comprising link sections directly contacting and rotatable about the pins of the links.

Signed at Chicago, Illinois, this 12th day of January, 1924.
